(57) **CLAIM**

The ornamental design for a door handle indicator for an image producing machine, as shown and described.

DESCRIPTION

FIG. 1 is a perspective view of a door handle indicator for an image producing machine showing the design of the present invention;

FIG. 2 is a front view thereof;

FIG. 3 is a left side view thereof;

FIG. 4 is a right side view thereof; and,

FIG. 5 is a top plan view thereof.

The broken lines shown are for illustrative purposes only and do not form part of the claimed design.
